United States Patent Office

Des. 196,619
Patented Oct. 15, 1963

196,619

FAN BLADE

Kenneth A. Merz, Cornwall, and Richard S. Morton, Winsted, Conn., assignors to The Torrington Manufacturing Company, Torrington, Conn., a corporation of Connecticut

Filed Feb. 8, 1962, Ser. No. 68,723

Term of patent 14 years

(Cl. D62—4)

FIG. 1

FIG. 2

FIG.3

FIG.4

FIG.5

FIG.6

FIG. 1 is a front view of a fan blade showing our new design;

FIG. 2 is a rear view of a fan blade;

FIG. 3 is a section taken on line 3-3 in FIG. 2;

FIG. 4 is a fragmentary section taken on line 4-4 in FIG. 2;

FIG. 5 is a section taken on line 5-5 in FIG. 1; and FIG. 6 is a fragmentary section in perspective taken on line 6-6 in FIG. 1.

We claim:

The ornamental design for a fan blade, as shown.
